(No Model.)

J. RENNEY.
IRONING TABLE.

No. 593,181.

Patented Nov. 2, 1897.

Inventor.
James Renney,
by R. L. Osgood
Attorney.

UNITED STATES PATENT OFFICE.

JAMES RENNEY, OF CHARLOTTE, NEW YORK, ASSIGNOR OF ONE-HALF TO
LUKE MARVIN, OF SAME PLACE.

IRONING-TABLE.

SPECIFICATION forming part of Letters Patent No. 593,181, dated November 2, 1897.

Application filed June 10, 1896. Serial No. 595,022. (No model.)

To all whom it may concern:

Be it known that I, JAMES RENNEY, of Charlotte, in the county of Monroe and State of New York, have invented a certain new and useful Improvement in Ironing-Tables; and I do hereby declare that the following is a full, clear, and exact description of the same, reference being had to the drawings accompanying this application.

10 My improvement relates to skirt-boards; and the invention consists of a combined skirt-board and receptacle constructed, arranged, and operated as hereinafter described and claimed.

15 In the drawings, Figure 1 is a plan view with the skirt-board partially broken away. Fig. 2 is a vertical cross-section. Fig. 3 is a sectional detail view.

A indicates the skirt-board, which is of ordinary form.

B is a receptacle. It consists of two half-sections *a a*, pivoted at *b* and provided with a central longitudinal axial bar *c* in line with the pivots. These sections can be opened 25 and closed as desired.

d d are rounds at the top of the receptacle, and *d'* is a round on one side attached to an extension of two of the arms and forming a holder for any articles placed thereon.

30 *ff* are two cross-bars pivoted on one side to the round *d* and engaging with the round *d'* on other side by means of open notches, thereby holding the receptacle extended.

g is a siding consisting either of wire or 35 cord passing alternately from side to side through holes in the rounds and also through holes in the center bar *c*.

The ironing-board A is supported by the cross-bars *ff* centrally over the receptacle 40 and is free at one end to be swung sidewise,

so that the skirt can be attached and removed over the free end. In the act of ironing the skirt is rotated laterally in the ordinary way, so as to bring new surfaces to the iron, and the body of the skirt is held in the receptacle 45 and prevented from escaping therefrom and coming in contact with any other surface. It therefore always keeps clean and requires no especial attention as to that matter.

Fig. 3 shows one end of the skirt-board attached to a pivot *h*, which passes through the cross-bar, and which pivot is of such length as to allow the board to be raised sufficiently to permit the passage of the skirt over the free end of the board. The board can be 50 swung crosswise, as shown in dotted lines. *k* is a stiff lug, of any suitable form, attached to the bottom of the board and turning with the board over the cross-bar to hold the board elevated.

Having described my invention, what I claim as new, and desire to secure by Letters Patent, is—

The combination of the receptacle B made in halves pivoted together, the cross-bars *ff* 65 pivoted on one side of the receptacle and connected detachably with the other, the skirt-board A resting on the bars, the elongated pivot *h* at one end attaching the board to the cross-bar, and the lug *k* for holding the board 70 elevated when turned to one side, as herein shown and described.

In witness whereof I have hereunto signed my name in the presence of two subscribing witnesses.

JAMES RENNEY.

Witnesses:

R. F. OSGOOD,
GEO. A. GILLETTE.
